ORNAMENTING MACHINE.

Application filed April 21, 1923. Serial No. 623,804.

This invention relates to machines for reproducing a pattern on the surface of jewelry or on other objects and consists in improvements whereby the construction of such machines is simplified, their functioning rendered more perfect and their output increased.

The illustrative embodiment of the invention is herein in the form of a machine wherein the design presented by a pattern may be reproduced on the surface of an object through the action of a traveler which is caused to pass relatively over the pattern, the traveler being adapted to respond to varying physical characteristics of the pattern and thereby to actuate a working tool operatively related to the object so that a predetermined design may be produced on the surface of the object.

While certain features of the invention may be embodied in machines of different types and employed for widely different purposes, in the illustrated embodiment of the invention the working tool is adapted to produce a design on the surface of an object and its movement is effected through devices controlled electrically by the traveler, and the design may be produced either by engraving or by an indenting action, adjustments being also provided whereby a so-called brocading effect may be produced at will.

The invention will be best understood by reference to the following description when taken in connection with the accompanying illustration of one specific embodiment thereof, while its scope will be more particularly pointed out in the appended claims.

In the drawings,—
Fig. 1 is a plan view of the machine embodying one form of the invention, certain of the upper portions of the machine being broken away for the sake of clearness;

Fig. 2 is a wiring diagram illustrating electrical connections for the machine;

Fig. 3 is a sectional elevation taken on the irregular line 3—3 in Fig. 1 showing the principal working parts of the machine;

Fig. 4 is a detail in end elevation showing the automatic releasing mechanism for the gearing which controls the carriages supporting the travelers and the working tools;

Fig. 5 is a sectional elevation in detail on the line 5—5 in Fig. 1 with the turret moved

to such a position as to show the action of the automatic ejector;

Fig. 6 is a rear elevation of the machine shown in Figs. 1 and 3 illustrating the driving gearing;

Fig. 7 is a sectional elevation on the line 7—7 in Fig. 1 showing the circuit controlling mechanism for the brocading attachment;

Fig. 8 is a sectional detail on an enlarged scale taken through the parts supporting and controlling one of the working tools;

Fig. 9 is a front view on an enlarged scale partly in section showing the arrangement of contacts controlled by the movement of the traveling follower;

Fig. 10 is a side elevation of the traveler and its supporting parts for the secondary pattern;

Fig. 11 is a front sectional elevation taken through the tool support in Fig. 8 showing the support for the working tool carrier;

Fig. 12 is a plan view of parts, some of which are shown in sectional side elevation in Fig. 8, which control the working tool carried in response to the secondary pattern;

Fig. 13 is a front elevation of the parts shown in Fig. 12;

Fig. 14 is a front elevation of a modified form of contact control which may be utilized in connection with the traveler;

Fig. 15 is a side elevation in partial section of the part shown in Fig. 14; and

Fig. 16 is a diagram illustrating the method of utilizing alternating current for producing a rosetting background.

Referring to the drawings and to the illustrative embodiment of the invention, we have there shown the latter as applied to a machine adapted to produce a surface ornamentation on an article or object pursuant to a predetermined pattern.

The invention may be embodied in machines for ornamenting articles of various shapes, sorts and sizes, but the illustrative embodiment thereof is constructed specifically to present to the working tool a work piece in the form of a small cuff button 15 (Fig. 3), the latter being brought by suitable devices, hereinafter described, beneath the tool carrier 17 and its tool, which latter has imparted to it a reciprocatory movement towards and from the face of the cuff button to produce, either by indentation or a cutting

action, as the case may be, the required design.

While the machine is in operation the tool is given a relative travel over the face of the work piece until it has traversed substantially its entire surface. This relative traverse may be secured in different ways, but herein the work piece is given a constant rotation while the tool is traversed across its surface radially from its outer border toward its center or axis of rotation, the working contact of the tool therefore taking place in a spiral path of decreasing radius, the pitch of the spiral depending upon the rate of inward travel of the carrier for the cutting tool.

In the illustrated embodiment of the invention a similar relative traverse is provided between the traveler which is represented at 19 and the pattern, which latter is herein in the form of a disc-like plaque 21, but which may take various forms or shapes. The plaque is rotated at the same rate as the work object and the traveler is fed across the plaque at a rate proportioned to the increased or decreased size of the pattern relatively to the work object. Herein the pattern is larger than the work object, being in the illustrated embodiment of the invention approximately six times the diameter of the cuff button, so that the traverse feed of the traveler is greater, and specifically six times greater, than that of the working tool.

Referring first to the devices for rotating the work and pattern supports and more specifically to Figs. 3 and 6, the machine is provided with the main drive shaft 23 which carries at its rear a driven gear 25 meshing with the driving pinion 27, which latter is driven through any suitable means, such as the pulley 29 and belt 31, from any suitable source of power.

The pattern is here shown supported in the cup-shaped turn-table 33 so as to have its upper face presented to the traveler 19, the turn-table being fixedly secured on the upright shaft 35, the latter journaled in the frame 37 of the machine. The shaft 35 is driven at the required speed through beveled gears 39 and 41 from the drive shaft 23. The cuff button or other work object is carried by a rotary work support 43 (Figs. 3 and 5) and, to permit the loading of the one or more work supports employed, the latter are each in the form of a rotatable sleeve mounted in a head or turret by which they may be brought successively into position beneath the working tool or tools. Herein the turret is composed of the drum-like member or head 45 having the top 47 and bottom 49 and mounted to be turned about the central upright post 51 secured to the frame of the machine.

The machine may be constructed to oper-

ate with a single work tool or with any required number of work tools all working in unison and controlled each by the same pattern and pattern traveler. Herein there are shown two work units each with a work tool and with duplicate actuating devices connected to be traversed simultaneously and each operatively related to any one of the four rotary work carriers with which the turret 45 is provided. It will be understood, however, that the same principles are applicable to machines provided with a larger number of work units, and in such case suitable modifications will be made in the arrangement of the turn-table and the number of its rotary work supports.

Herein, however, to cooperate with the duplicate work tools there are provided four rotary supports so distributed in the turn-table that, while two of them are presenting their work pieces to the respective work tools, the others may be undergoing loading.

To rotate each work support there is provided at the upper end of each sleeve 43 a gear 53 which meshes with a central gear 55, the latter secured to the upright shaft 57 journaled in the post 51. The shaft 57 is rotated by the shaft 23 through beveled gears 59 and 61, the gearing being proportioned so that the speed of rotation of each work support is the same as that of the pattern.

The rotary work supports 43 which are simultaneously and constantly rotated and are journaled in the upper and lower plates 47 and 49 of the turret, are each provided with devices adapted to hold the work piece while the latter is under the work tool, but permitting the work piece to be inserted at will and easily withdrawn therefrom. For this purpose there is provided in each rotary support a chuck 63 comprising the sleeve 65 which is split to provide resilient spring fingers which tend to open or spread apart when unconstrained, the lower end of the sleeve being threaded or otherwise secured to the plunger 67 which is normally depressed by the spring 69, one end of which abuts against the head 71 of the plunger and the opposite end against a wall within the rotary work support. When the plunger is lifted (as shown in Fig. 5) the fingers are projected above the surface of the turret plate 47 and they are of such size and shape as to readily receive the cuff button 15. When the spring 69 is permitted to depress the plunger to its normal position (as shown in Fig. 3), the recess provided by the rotary work support and into which the upper flared end of the fingers are retracted, is of such shape as to contract the fingers and grip the cuff button, leaving the working surface thereof projecting just above the upper plate of the turret (as shown in Fig. 3).

- During the operation of the machine the turret is held in fixed position to suitably align the work supports with the working tools by any suitable means, such as the
- 6 spring pressed locating pin 73 which is mounted on the machine frame and engages a recess in the turret 45. After the machine has completed its operation the turret is turned by hand 180°, where it is
- 10 again located or centered by the pin 73, and the finished buttons having been automatically discharged, as hereinafter described, the two empty work supports are then re-loaded.
- 15 To assist in reloading there are provided the two pivoted levers 75, the inner ends of which are positioned one beneath each one of the two plungers 65 for the empty chucks. Each lever is normally pulled down
- 20 against the stop pin 77 by a spring 79. To load the chuck the operator presses down on the lever 75, lifting the plunger and projecting and expanding the jaws or fingers of the chuck (as shown in Fig. 3), in
- 25 which position an unornamented cuff button is inserted. The lever being then released, the fingers retract and hold the cuff buttons in position ready for presentation each to its tool, when the turret is again
- 30 turned.
- To provide for the automatic discharge of the button or other work object after the work has been completed and the turret turned, automatic means are preferably
- 35 provided, herein in the form of a cam formation 81 (Figs. 1 and 5), located on the machine frame and lying within the path of the plunger head 71, so that as the rotary work support travels from its work
- 40 position to its loading position each plunger rides over the cam and lifts the chuck, automatically releasing the button. To insure its discharge from the chuck when released, there is provided a small ejector
- 45 pin 83 arranged centrally within the chuck between the spring fingers thereof, such pin being slidably mounted in a tubular support 85 secured to or carried by the plunger 67 and pressed upward by the small internal spring 87 so that the top of the pin
- 50 presses against the bottom of the cuff button. When the button is inserted in the chuck the pin is depressed against its spring. When, however, the jaws of the chuck are
- 55 opened by the lifting of the plunger 67 the spring acts to eject the button from the jaws of the chuck. To automatically discharge the button and clear it from the face of the turn-table means may be provided, such as the plate and chute 89 (Fig. 1), one side 91 of which acts to guide the released and ejected button into the inclined portion of the chute as the turn-table completes its movement, the successive
- 60 buttons being thereby conveyed one by one
- into the inclined portion of the chute and discharged by gravity into any desired receptacle (not herein shown) beneath the same.
- Through the described mechanism it will be observed that the pattern carrier and each one of the rotary work supports are given a constant rotation in operative relation respectively to the traveler 19 and the several tool carriers 17.
- Referring now to the devices for imparting a transverse feed of the traveler radially across the pattern and a similar feed to each of the work tools across its respective work piece, the traveler and its associated parts are supported by a depending support plate 93 (Figs. 3 and 9) which is secured to a horizontally sliding carriage 95, the latter mounted to slide in guideways formed in the head 97 of the machine. Suitable travel of the carriage is effected by means of the feed screw 99 which engages with the carriage nut 101. Similarly each work tool carrier with its associated devices is mounted on a depending supporting plate 103 secured to the carriage 105 to which a transverse feed is imparted by means of the feed screw 107 and the cooperating carriage feed nut 109.
- To maintain the proper relation of the feeds, intermeshing gearing is provided between the two feed screws, such gearing comprising the pinion 111 (Fig. 3) on the feed screw 99, the intermediate gear 113 and the intermeshing gear 115 on the feed screw 107, the position of the carriage supports and guide and the position of the gearing being such that, starting with the traveler at the extreme outer edge of the pattern or plaque, the traveler moves radially inward until it reaches the center of the plaque, and at the same time each of the working tools is moving from the extreme outer edge of its respective cuff button, or that portion of it to be ornamented, to the center thereof.
- To effect simultaneous movement of the two carriages the shaft for the feed screw 107 has secured at its outer end the worm gear 117 which meshes with the worm 119 on the worm drive shaft 121. Movement is imparted to the worm drive shaft through the pinion 123 (Figs. 3 and 6), the latter meshing with the drive gear 125.
- The gear 125 is driven from the main drive gear 25 through intermediate gearing which provides for changes in the rate of feed whereby the traverse of the traveler with relation to its pattern and of each cutting tool with relation to its work object may be varied, and the distance between successive spiral paths of the traveler and the tools be made greater or less according to requirements and the appearance of the design thereby materially altered. Such variation in the feed may be effected in various ways.

4
Herein there are provided three gears 127, 129 and 131 of different pitch diameter mounted on the stud shaft 133, the latter supported by a radial arm 135 which is pivoted on the shaft 137 carrying the gear 125. The arm 135 may be clamped in any desired position by means of the clamping screw 139 which passes through a slot in the arc-shaped arm 141, the latter having a center coinciding with the shaft 137. The gear 25 is adjustably secured to the shaft 23 by any suitable means, such as a set screw, so as to be capable of adjustment to different positions longitudinally of the shaft and to align with any one of the gears 127, 129 or 131. By loosening the clamp screw 139 the radial arm 135 may be dropped down to different positions bringing any one of the gears 127, 129 and 131 into mesh with the gear 25. By this means three different rates of feed may be provided for the traveler and the work tools for the same speed of rotation of the pattern and work supports. Any desired number of speed changes, however, may be produced by the provision of additional change gears.

Any desired provision may be employed for stopping the machine after a work piece or set of work pieces has been finished, and for starting it up again after the turntable has been turned to present new work pieces to the tools. Herein we have shown means for accomplishing this by throwing the carriage feed driving mechanism into or out of engagement, the pattern carriage and the work supports continuing their rotation between successive stages of operation of the machine. There may also be provided, as herein shown, devices for automatically stopping the traveler and work carriages when the traveler and work tools have reached the limits of their working traverse, herein the respective centers of the pattern and work object. In the illustrated embodiment of the invention the machine is such that the feed automatically stops when that stage is reached, permitting the carriages to be quickly returned by manual means to their initial positions and leaving the gearing ready to be started as soon as the turret has been moved to bring a new set of work pieces under the work tools.

For this purpose the worm shaft 121 has its rear end journaled in a support 142 (Figs. 1, 3 and 6), swiveled on the upright bracket 143 permitting a slight rocking movement thereof and permitting the worm 119 to be thrown out of mesh with the worm gear 117. The opposite end of the worm shaft is journaled in a block 145 which, during the operation of the machine, is so held down as to cause the engagement of the worm and worm gear by means of a pivot catch finger 147 (Fig. 4) pivoted at 149 and normally drawn by the spring 151 to lock

the block down in position. If the block is released, however, by the outward movement of the catch, it will be thrown upward by the underlying spring 153 against an abutment 155 presented by the machine frame. The face of the block on opposite sides bear against guiding surfaces on the machine frame.

The upward movement of the shaft, when released by the catch, disengages the worm gear. To provide means for causing this automatically to take place when the traveler and the working tool have reached the centers respectively of the pattern and work object, the catch 147 is controlled by a lever arm 157 pivoted at 159 on the underside of the machine head, the lever at its front end having a bent portion 161 slotted to receive the depending lower end of the catch. The opposite end of the lever lies within the path of a depending screw 163 which may be adjustably located in different positions on the traveler carriage 95, so that when the carriage reaches the end of its feeding movement the lug engages the lever and moves it to throw the catch and release the block 145, thus throwing out the feed gearing, this being herein arranged to take place at the time the traveler reaches the geometrical center of the pattern.

After the feed has been stopped the carriages may be quickly returned by any suitable means to their initial positions preparatory to the next operation, there being herein provided for that purpose the crank handle 165 which is connected directly to turn the fine feed screw 107. A very few turns of this crank handle serve to return the two carriages simultaneously to their initial positions. After the two feed carriages have been moved back by the crank handle and the turret has been turned to present fresh buttons or work objects to the action of the working tools, the feed of the carriages is again initiated by throwing the feed worm 119 into mesh with the worm gear 117, which can be readily done by manually drawing down the feed shaft 121. For that purpose the latter is provided with a manually engageable, projecting forward end 167. When thus drawn down, the worm is brought again into mesh with the gear, the spring 153 compressed, permitting the latch 147 to snap into engagement with the journal block 145 and the trigger lever 157 to be simultaneously drawn back with the latch into suitable position to be engaged by the traveler carriage on the completion of its next working movement.

Referring now to the devices for controlling the working movement of the traveler, the pattern is herein provided with a surface having a varying contour, the pattern being presented by successive relatively high

and low portions in contrast, these being utilized to impart a rising and falling movement to the traveler 19, which is kept in contact with the pattern face as the combined rotary movement of the pattern and the radial feeding movement of the traveler cooperate to cause a spiral traverse of the traveler over the face of the pattern, this in turn effecting a rising and falling movement 10 of the traveler corresponding to the successive relative elevations and depressions of the pattern. This rising and falling movement is herein availed of to control the operation of the working tool as a like relative travel 15 of the latter over the work object simultaneously takes place.

The varying contour may be presented either by a design created in relief on the one hand or by incision or intaglio on the 20 other hand, or pattern characteristics other than those of varying contour may be availed of to secure the necessary movement of the traveler. Certain features of the invention more broadly considered, 25 moreover, may be usefully applied to machines wherein the traveler executes no reciprocatory movement, but variations in other physical characteristics may be relied upon to cause the traveler to produce the 30 required action of the working tool.

In the illustrated form of machine the relative travel of the traveler over the pattern is utilized to move the working tool first toward the work object and then away 35 from the latter as successive portions of the pattern are encountered by the traveler. This may be accomplished in various ways, but in the illustrated embodiment of the invention the rising and falling movement 40 of the traveler is utilized to control electrical circuits which cause the actuation of electric devices for the working tool, the latter also in the specific form of the invention shown being positively moved first in one direction 45 by such electric devices and then positively in the opposite direction also by electric devices, this being in response to opposite movements of the traveler. Many of the features of the invention may be utilized 50 with tool actuating devices of other types, but in the specific embodiment illustrated this arrangement of the traveler not only avoids the necessity of using the surface of the pattern as an electric contact, 55 thereby avoiding sparking at the pattern and burning and disfiguring the same, but permits the use of positive electrical actuation of the working tool in both opposite directions, increasing the quickness of its response 60 to the movement of the traveler, its efficiency of operation, and in the case of engraving work adding to the quality of the design. As will be hereinafter explained, 65 in the case of indenting work, a superior result may often be had by moving the tool

towards the work by electrical means and relying on a spring or its equivalent to move it in the opposite direction.

Referring to the parts associated with the traveler and more particularly to Figs. 70 3 and 9, the traveler is secured to the lower end of an upright reciprocatory contact-carrying rod or pin 171 which is mounted to slide in a guide block 173 secured to the depending carriage plate 93. Near its upper end the rod carries a laterally extending contact member 175 insulated from the rod and out of electrical contact with the machine frame but connected to the conductor 177. In the lower position of the 75 traveler the member 175 makes contact with the contact pin 179 (Fig. 9), which latter has electrical connection with the conductor 181. The contact pin 179 is arranged to yield slightly under the downward pressure 80 of the contact member 175 and is also provided with means whereby it may be accurately and nicely adjusted to time the point of initial contact. For this purpose it is provided with the enlarged head 183 85 which is slidable within the sleeve 185, the lower end of the contact pin being threaded to receive the adjusting nut 187 which latter abuts against the lower end of the sleeve. The spring 189, one end of which abuts 90 against the end of the sleeve and the opposite end against the enlargement 183, presses the pin to its uppermost position which is determined by the position of the nut. These contact devices are supported by a 95 bracket 191 carried by the carriage plate 93, there being provided an intermediate insulating sleeve 193 which prevents the grounding of the circuit. In timing the contact pin 100 the nut is turned until the contact pin is positioned at the point where initial contact is desired and the nut is then fixed in position by a set screw.

Axially aligned with the upper end of the rod 171 and in cooperative relation thereto there is provided a second contact pin 195 mounted within a sleeve 197 supported by the bracket 199 and insulated therefrom by a sleeve 201, the contact pin 195 and its associated parts being in all 110 respects substantially the same as those already described in connection with the contact pin 179. The pin 195 is in electric contact through the adjusting nut 203 with the electric conductor 205. When the traveler moves up under the control of the pattern, contact is made between the pin 195 and the slide rod and the latter, being grounded through the frame of the machine, as is hereinafter described, the conductor 205 is 115 thereby grounded.

When the traveler moves up, therefore, the lower contact and its corresponding circuit are broken and the upper contact and 120 its corresponding circuit are made. When 125

the traveler moves down the reverse action takes place. The adjustability of both sets of contacts permits such adjustment that one circuit may be made at the same time the other is broken, or such adjustment can be had that each circuit is made before the other circuit is broken. The latter adjustment permits the magnetic effect in one set of actuating magnets for the working tool to be built up before the remaining set of actuating magnets is deenergized, so that the tool acts with a quick snap and without any lag which might be otherwise experienced, thereby increasing the responsiveness of the tool.

The traveler rod is normally depressed to a definite lowermost position, which is carefully determined with reference to the pattern holder or the contour of the pattern, by means of the light spring 207 which is confined between an enlargement 209 on the lower end of the contact pin and the lower face of the guide block 173. To secure a nice adjustment of the lowermost position of the pin, the upper end of the traveler rod is threaded and carries an adjusting nut 211 provided with a set screw or other means to fix it in position, which nut rests against the upper face of the guide block 173 defining the lowermost position of the traveler and limiting its downward movement.

Referring now to the parts associated with the working tool or tools, and more particularly to Figs. 3, 8 and 11, these parts are substantially duplicated in each tool unit, the illustrated form of machine being provided with two such units respectively, operatively related to the work-piece holders which appear in Fig. 1 approximately under the feed screw 107. In each tool unit the tool carrier 17 (Fig. 8) is in the form of a vertically movable slide rod 17, slidably mounted in the guide block 213, the latter in turn being capable of whatever up and down movement is required for working on objects of different or varying height by provision of vertical guideways 215 formed in the depending carriage plate 103. This vertically movable slide 213 is provided at its lower end with a depending guide foot 217 which is located close to the working tool and may be forked or of any other shape to suit the character of the work, its function being to keep the proper working distance between the tool and the work, whether working on curved, flat or irregular surfaces. The guide foot is normally held down against the work or turntable face by a spring 219 interposed between the upper end of the slide block and the lower face of the carriage 105, the spring exerting a sufficient thrust to provide all necessary reaction for the blow or pressure of the cutting tool. It will be seen, therefore, that as the

cutting tool performs its relative traverse over the surface of the work object, the guide foot maintains the same working relation between the tool and such surface, the slide moving up or down by the action of the guide foot and the spring as may be required to conform to variations in the height of the surface of the work object.

The working tool 221 itself may be either a cutting point for engraving or incisive ornamentation, or an indenting point for broaching work, as will be more fully described, the lower end of the tool carrier 17 being arranged, for example, with a tapered tool holding socket so that a variety of different forms of working tools may be used interchangeably.

Referring now to the electrical devices which actuate the work tool under the control of the traveler, the upper end of the tool rod 17 is provided with an armature 223 operatively related to two sets of magnets, one of which 225 is located above the armature and acts positively to elevate the tool, and the other of which 227 is below the armature and acts positively to depress the tool.

Devices are also provided for accurately regulating the throw or stroke of the tool carrier as well as its upper and lowermost positions, and also for limiting the minimum distance between the armature and the poles of each set of magnets so as to prevent either sticking or drag. To this end the upper end of the tool rod is threaded and provided with a member 229 adapted to rest upon the upper face of the slide block and determine the lowermost position of the tool relatively to the slide block and guide foot 217. This adjustment which constitutes one of the preliminary settings of the machine determines the lowermost position of the work tool and therefore the depth of cut or indentation, as the case may be. The threaded member 229 may consist of a nut having means, such as a set screw, to set it in fixed position after the initial adjustment has been made, but herein it is shown in the form of a nut having gear teeth formed in its periphery and associated with devices which are capable of effecting, during the operation of the machine, an adjustment of the nut and thereby the depth of cut or indentation, as will hereinafter be more fully described.

The length of stroke of the tool carrier and the uppermost position of the tool are determined by the position of the adjustable member 231 (Figs. 8 and 11) secured to the lower protruding end of the tool rod and adapted to abut against the lower face of the slide plate 213. This is held in fixed and nicely adjusted position by means of the adjusting nut 233 which engages the lower threaded end of the tool rod. In the

illustrated form of the invention, as shown in Fig. 11, the limiting member 231 is provided with side extensions to which are secured the pins 235 which enter recesses in the lower face of the slide block and are pressed downwardly by springs 237 so that the downward pull of the depressing magnets 227 is supplemented by the thrust of the springs 237. The springs may be omitted, however, if desired.

The lower or depressing set of magnets 227 are carried (Fig. 3) upon a supporting plate 239 which is secured to the slide rod 213 by means of the set screw 241 passing through a slot in the plate, so that the magnets are capable of a limited up or down adjustment. This permits the magnets to be accurately adjusted after the limiting positions of the tool rod have been determined to secure the required minimum gap between the armature 223 and the poles of the magnets and prevent the armature from such close working proximity to the magnet poles as to create any tendency to stick or drag.

Similarly the upper or elevating set of magnets 225 are supported upon a plate 243 secured to the slide rod by the set screw 245 passing through a slot in the plate, so that these magnets may be similarly adjusted with reference to the extreme upper position of the armature 223 to provide the required gap.

The rod 17 is prevented from turning by the threaded pin 224 seated in the plate 213 and engaging a groove in the rod.

This arrangement of actuating devices for the tool carrier provides for a rapid, quick, snappy action of the tool in both opposite directions and under the precise control of the follower (as will hereafter appear), while the adjustments, particularly in connection with the adjustments for the contacts at the traveler rod, permit the movement of the tool to be nicely predetermined and prevent missing or lag or drag in its response. The detailed and specific construction of the parts shown for purposes of adjustment and for preventing the sticking of the armature due to contact with or proximity to the magnet poles, are illustrative only, and equivalent results within the broad spirit of the invention may be secured by widely different means.

In the case of indenting work, as distinguished from engraving, good results may be had by omitting the lifting magnets 225 and the traveler-controlled contacts and circuits governing the excitation of these magnets and substituting therefor as a lifting agent a lifting spring. Such spring may be used in substitution for the depressing springs 237, shown in Fig. 11, or, the springs 237 being omitted, the lifting spring may be elsewhere located with reference to the tool carrier rod. This lifting spring may

be relatively weak so as to give only a partial lift without causing the tool actually to clear the surface. The use of such a spring in substitution for the lifting magnets results in very sharp and fine indentations by the working tool under the control of the traveler and depressing magnets, giving a relatively soft and fine background for the design appearing in relief.

The mechanism so far described is substantially complete for the purpose of an engraving or cutting action. Means, however, are additionally employed whereby the action of the working tool may be modified more or less during the operation of the machine to produce predetermined ornamental effects in certain portions of the pattern, or additional pattern devices may be employed for further modifying the action of the tool so that, through electrical devices or otherwise, the effect of such additional pattern devices may be superposed upon the effect of the main pattern.

The invention broadly as to many of its features is susceptible to application to a great variety of such uses, but for illustrative purposes there is shown applied to the described form of the machine a mechanical attachment to produce the so-called rosetting effect, whereby the tool, when used for indenting purposes, may be given a series of rapid movements in those parts of the work which correspond to the depressed portions of the pattern, thereby imparting to the design a background composed of dots or lines, and such dots or lines may be, according to the method of control, arranged in a variety of designs, as, for example, in a radial or dial form or in a staggered, matted or overlapping form.

In the form of the invention illustrated in Figs. 1 to 15 inclusive, this so-called rosetting effect is produced by rapidly making and breaking the circuit for the magnets acting to depress the working tool during the time the traveler is in the depressed portions of the plaque, in which position it acts to close the circuit through those magnets. This results in giving an initial downward impulse to the indenting tool when the traveler first moves down and this is followed by a succession of rapid relaxations and pulls as the circuit is rapidly made and broken while the traveler remains depressed.

In connection with Fig. 16, I have disclosed a method by which the rosetting effect may be effectively produced without the necessity of a special circuit breaking attachment.

Referring to Figs. 1, 3, 6 and 7 and more specifically to Fig. 7, which illustrates the mechanical rosetting attachment, the circuit 247 is caused to pass through contact devices controlled by a rosetting wheel 249

by which it is capable of being rapidly interrupted. The conductor 247 is herein shown connected to a yieldable contact pin 251 similar in its general construction and 5 as to its associated parts with the contact pins 179 and 195 shown in Fig. 9. This contact 251 is in operative relation to a second contact pin 253, the inner end of the latter being adapted to bear against the 10 periphery of the rosetting circuit interrupting wheel 249. The pin 253 is slidably mounted in a cylindrical casing 255, the latter supported by the bracket 257, which bracket is secured to the frame of the 15 machine but insulated therefrom by the strip of insulating material 259 (Fig. 6). A spring 261 within the barrel forces the head of the contact pin 253 against the periphery of the rosetting wheel, a stop pin 263 being provided to limit the movement thereof.

The bracket 257 is connected to the conductor 181 so that when the two contact pins are separated the tool depressing circuit is opened at that point. The rosetting wheel 249 has a toothed periphery so that when the wheel is rotated the pin 253 is rapidly reciprocated and the circuit given a series of rapid makes and breaks. This causes successive relaxations in the impulses imparted to the tool when the traveler is depressed and the character of these impulses and the appearance of the background produced in the design thereby may be widely varied by altering the pitch and shape of the teeth on the wheel 249, as well as by varying the speed of rotation with relation to the rotation of the pattern carrier. To turn the rosetting wheel the latter is secured to but insulated from an upright shaft 265 carrying the gear 267, the latter meshing with the pinion 269 which is driven in turn by a gear 271 secured to the upright shaft 35 for the pattern carrier.

To permit any desired variation in the relative speed of rotation of the rosetting wheel the shaft for the pinion 269 is carried by a bracket 273 (Fig. 7) adjustably secured to the frame of the machine by a set screw 275 passing through a slot in the bracket. By removing the rosetting wheel from its shaft, the gear 267 may also be removed and replaced by a gear of different size and the bracket then adjustably shifted to bring the pinion 269 into mesh with both the gear substituted for the gear 267 and with the pattern shaft gear 271. By providing for the rate of rotation of the toothed wheel similar to or an even multiple of that of the pattern, a rosetting effect may be made in a dial or radial form, or, by changing the gearing ratio, it may be made to appear in a staggered or over-

lapping form, or spiral effects may be obtained.

The control of the working tool through the movement of the traveler when the machine is employed as a broaching machine with an indenting tool and with the rosetting attachment described will be evident from the diagrammatic representation in Fig. 2. One terminal of the upper or elevating set of lifting magnets 225 is there shown as connected to the battery 277, the remaining terminal to the battery being grounded at 279 to the frame of the machine. The traveler rod 171 is also grounded at 281 to the frame of the machine so that as the traveler moves up the magnet circuit is closed through contacts 171 and 195, energizing the magnets and elevating the tool.

On the other hand, one terminal of the depressing magnets 227 is connected through the conductor 247 and battery 248 with the rosetting contact 251, the remaining terminal being connected through the conductor 177 with the contact 175 at the traveler. The remaining contact 179 thereat is connected to the contact 253 at the rosetting wheel. When the traveler is depressed, therefore, the depressing magnet circuit is closed at the traveler and remains closed at that point so long as the traveler is depressed, the magnet circuit, however, as a whole being ultimately broken and made by a series of rapid interruptions through the action of the rosetting wheel 249, thus producing on the work object a series of fine indentations during such times as the traveler remains depressed.

To protect the various contacts against damage from arcing, condensers 283 and 285 are preferably employed. When the machine is to be employed as an engraving machine the rosetting attachment may be omitted and the depressing magnet circuit uninterrupted except at the traveler control contacts 175 and 179.

Referring now to devices which may be utilized to superpose on the design produced by the main pattern, also design effects controlled by supplemental or secondary patterns, there is herein shown as one illustrative embodiment thereof a supplemental pattern carrier 289 (Fig. 1) which may be utilized to modify the action of the working tool while the latter is being actuated by the main pattern. In the illustrative case this is carried out by means acting to vary the permissible depth to which the tool may move when it is being impelled toward the work and such means are shown in connection with the rosetting attachment so that it is utilized to modify the rosetting effect, thereby securing a supplemental design through the effect of a more or less

shaded background. The invention in its broad aspect, however, may be carried out by modifying the action of the cutting tool in other ways and by a modified action of 5 the cutting tool without reference to the rosetting attachment.

In the specific form of the invention herein shown the supplemental pattern carrier 289 carries a plaque which is rotated by means 10 of a gear 291 meshing with an intermediate pinion 293 driven from the pattern shaft gear 271. The plaque is rotated thereby at the same rate of speed as the main pattern and in the same direction but in operative 15 relation to a supplemental traveler 295 (see Fig. 10) which is supported to move with the pattern feed carriage 95. The secondary pattern is herein provided with a varying contour, the successive elevations and depressions of which are arranged with reference 20 to some predetermined design, such contour variations, however, occurring only in those portions of the secondary plaque which are brought under its traveler at the same 25 time that the depressions in the main pattern are brought under the main traveler. The secondary traveler 295 is mounted upon a vertically movable slide rod 297 (Fig. 10) slidably mounted in the guide block 301 carried 30 by the depending plate 303 secured to the main feed carriage 95, the lowermost or initial position of the secondary traveler being accurately determined and adjusted by the threaded nut 305 at the upper end of 35 the slide rod 297. The secondary traveler rod carries in insulated relation thereto the laterally extending contact arm 307 adapted to engage with the yieldable contact pin 309 when the traveler is lifted by its pattern, the 40 contact 307 being connected to the conductor 311 and the contact pin 309 to the conductor 313. The yieldable contact pin 309 and its associated parts are of substantially the same construction as those shown in connection 45 with the contact pin 179 in Fig. 9.

When the machine is in operation and the supplemental traveler 295 is raised and lowered by engagement with successive elevations and depressions in the secondary pattern, the contacts 307 and 309 are successively brought together and separated making and breaking the circuit containing conductors 311 and 313. Referring to the diagram in Fig. 2, it will be seen that these 50 conductors are connected to opposite terminals of the magnet 315 and battery 317, or other source of current being provided, and preferably a condenser 319 in shunt to the contacts 307 and 309, so that as the described action takes place the magnet 315 is alternately energized and de-energized.

Referring to Figs. 8, 12 and 13, the effect 55 of this action upon the cutting tool will now be explained. The magnet 315 mounted upon a preferably non-magnetic bracket 321

is secured to the front of the slide block 213 and is operatively related to an armature 323 which depends from the under face of a small gear 325. The gear 325 meshes with the teeth of the threaded nut 229 and 60 is capable of limited movement through the provision of the pin 327 located in the bracket 321 and works in the slot 329 in the gear. The gear is held in a normal position by means of the spring 331 which 65 holds it to the limited position permitted by the slot, and in this position it holds the toothed threaded nut 229 at the point where it provides the normal working depth for the working stroke of the tool. When the 70 magnet 315 is energized, however, it attracts the armature 323 and moves the gear 325 to the furthermost position permitted by the pin and slot, and by so doing turns the 75 adjusting nut 229 so as to slightly increase 80 the depth of the working stroke of the tool. The pin and slot are so located as to prevent actual contact with the pole of the magnet and the latter is preferably secured to an 85 L-shaped piece 333 of magnetic material, the 90 opposite end of which terminates adjacent the armature so as to increase the efficiency of the magnetic circuit. The result is that, as the secondary follower rises and falls, and the magnet 315 is energized and deenergized, a back and forth annular movement 95 of the gear 325 and the adjusting nut 229 is effected and variation in the depth of the working tool stroke follows which results 100 in changing the appearance of the rosetting, or of the background, if employed without the rosetting attachment, such variation following the predetermined design afforded by the secondary pattern. The secondary pattern may act through a suitable relation of 105 the magnet 315 and gear 325, momentarily to decrease the depth of the working stroke of the tool or, as shown in the drawings, serve to increase the depth of such working 110 stroke.

It may be observed that by adjusting the contacts at the main traveler, the contacts at both top and bottom may be prolonged or shortened to any desired extent so as to alter somewhat the action of the tool and 115 the appearance of the design where the same pattern is utilized.

It will be observed that the use of electro-magnets for positively imparting opposite movements to the tool carrier provides 120 for an increasing pull or impulse toward the end of the stroke, thereby increasing the rapidity and responsiveness of the tool to the traveler.

In Figs. 14 and 15 there is shown a modified form of contact mechanism controlled by the movement of the traveler, the contacts being carried and supported by a device independent of the traveler and actuated merely by traveler movement. This 125 130

permits the movement of the traveler to be multiplied in the resulting movement of the contacts so that it provides a means for reproducing the design with increased sharpness.

Referring to Figs. 14 and 15, the contact mechanism there shown is actuated by engagement between a collar 341 carried by the upper end of the traveler rod 171 and the overlying part 343 on the lever arm 345, the latter being pivoted at 347 on the traveler support 93. The lever is moved to cause the part 343 to follow the downward movement of the slide rod by means of a spring 349 secured to a projection 351 attached to the lever 345. The latter has secured thereto but insulated therefrom a plate 353 which is connected to the conductor 177, such plate carrying the contact pin 355 while the lever arm 345 carries a second contact pin 357. The contact pin 355 is operatively related to an adjustable contact 359 and the pin 357 to an adjustable contact 361. The contact 359 is carried by a plate 363 and the contact 361 by a plate 365, both plates 365 and 363 being secured to but insulated from a slide 367 mounted to slide transversely in guideways formed in the support 93.

When the traveler moves upward it engages the projecting portion 343 of the lever 345 and imparts a clockwise swinging movement of the latter, bringing the pin 357 into engagement with the contact 361 and withdrawing the pin 355 from engagement with the contact 359, thereby grounding the circuit 205 and breaking the circuits 181 and 177. The further upward movement of the traveler causes a movement of the entire slide to the right, as viewed in Fig. 14. When the traveler descends the spring 349 moves the lever in the opposite direction, separating the contacts 361 and 357 and causing engagement between contacts 355 and 359, the slide 367 continuing thereafter to move in the opposite direction until brought to rest by the adjustable stop pin 369. This stop pin may be so adjusted as to leave any desired lost motion between the collar 341 and lever portion 343, permitting, therefore, the contacts 355 and 359 to be separated immediately on the commencement of the upward movement of the traveler or to remain in engagement for any desired part of that upward movement.

When the traveler moves upwardly and the slide is moved right-handedly, as viewed in Fig. 14, the contact pin or screw 361 may be caused to engage with a spring-pressed abutment 371, the latter being preferably adjustable so as to permit it to yield by a greater or lesser amount as may be desired. When the traveler reverses its movement, this abutment is effective to move the slide left-handedly, maintaining the contacts 357

and 361 in engagement for a certain interval of time and preventing, during that interval, the engagement of contacts 355 and 359 which control the tool-depressing magnets 227. This prevents any slight variation in the height of the raised surfaces of the pattern from altering the action of the working tool in its response to the depressed portions of the pattern.

In Fig. 16, I have illustrated diagrammatically a method of and apparatus for securing the rosetting effect without the necessity of mechanically making and breaking the circuit of the working tool magnets in order to produce the series of indentations which is required. The corresponding parts shown in this diagram are designated by numerals similar to those employed in connection with Fig. 2. In this case the tool depressing magnets 227 only are employed, the upper set of magnets 225 being omitted, and the tool being refracted by a relatively weak lifting spring 381, which is preferably of sufficient strength to cause the tool barely to clear the surface of the work object. The traveler 171 is provided with contacts 175 and 179 only, which act to control the energizing circuit 205, the latter, however, being connected to a source of alternating current supply 383 so that the magnet 227, instead of being energized by direct current, is energized by alternating current. This may be obtained, for example, by connecting the magnet circuit to a lamp socket on an ordinary alternating current lighting circuit. Such a current with a periodicity, for example, of sixty cycles per second will impart to the working tool, during such times as the traveler is occupying its depressed position with relation to the pattern, a series of vibrations of sufficient rapidity to produce a rosetted background of a softness and quality which cannot be secured by any ordinary mechanical means. The fineness of these indentations may be varied by varying the speed of rotation of the pattern and of the work object.

While we have herein shown and described for the purposes of illustration one specific embodiment of the invention and the application of one form thereof to a specific work object, it is to be understood that the same may be utilized for the ornamentation of various objects and for the production of design effects departing widely from those herein described; furthermore, that the details of construction and the specific arrangement of parts may be widely varied without departing from the spirit of the invention as expressed by the following claims, and that many of the features herein described may be utilized either in the form herein shown or in widely different forms and in connection with mechanisms or devices used for purposes other than the one

herein described or differing widely from those herein shown.

Claims:

1. In a pattern controlled reproducing machine, the combination with a rotary support for a pattern plaque having a varying contour, of a traveler with a reciprocatory plunger, devices for causing relative traverse between the face of the plaque and the traveler while the latter is in contact with the former, said traveler having imparted thereto a reciprocatory movement responsive to the varying contour of the pattern, a rotary work support, a tool, a reciprocatory tool carrying rod movable independently of the traveler, a magnet for moving the tool carrying rod and tool directly away from the work, a controlling circuit for the magnet, and contacts extraneous of the pattern and controlled by the pattern-caused movement of the traveler plunger whereby movement of the tool follows movement of the traveler. 65
2. In a pattern controlled reproducing machine, the combination with a rotary support for a pattern plaque having a varying contour, of a traveler with a reciprocatory plunger, devices for causing relative traverse between the face of the plaque and the traveler while the latter is in contact with the former, said traveler having imparted thereto a reciprocatory movement responsive to the varying contour of the pattern, a rotary work support, a tool, a reciprocatory tool carrying rod movable toward and away from the work independently of the traveler, a magnet for moving the tool carrying rod and tool directly away from the work, a controlling circuit for the magnet, and contacts extraneous of the pattern and controlled by the pattern-caused movement of the plunger whereby movement of the tool follows movement of the traveler. 70
3. In a pattern controlled reproducing machine, the combination with a rotary support for a pattern having a varying contour, of a traveler, devices for causing relative traverse between the pattern and traveler while the latter is in contact with the former, said traveler having imparted thereto a reciprocatory movement responsive to the varying contour of the pattern, a rotary work support, a tool, the latter mounted for reciprocatory movement toward and away from the work, a magnet for moving the tool directly in relation to the work, a controlling circuit for the magnet, and contacts extraneous to the pattern and controlled by the pattern-caused movement of the traveler whereby movement of the tool follows movement of the traveler. 75
4. In a pattern controlled reproducing machine, the combination with a pattern support for a pattern having a varying contour, of a traveler with a reciprocatory plunger, devices for causing relative traverse between the face of the plaque and the traveler while the latter is in contact with the former, said traveler having imparted thereto a reciprocatory movement responsive to the varying contour of the pattern, a work support, a tool, a reciprocatory tool carrying rod movable independently of the traveler, a magnet for moving the tool carrying rod and tool directly away from the work, a controlling circuit for the magnet, contacts extraneous to the pattern, and a movable actuator set in action by the movement of the traveler for controlling the contacts whereby movement of the tool follows movement of the traveler. 80
5. In a pattern controlled reproducing machine, the combination with a support for a pattern having a varying contour, of a traveler, devices for causing relative traverse between the pattern and the traveler while the latter is in contact with the former, said traveler having imparted thereto a reciprocatory movement responsive to the varying contour of the pattern, a work support, a tool, a magnet for moving the tool directly in relation to the work, a controlling circuit for the magnet, and contacts controlling said circuit and controlled by the pattern-caused movement of the traveler to move the tool in response to pattern-caused movement of the traveler. 85
6. In a machine of the class described, the combination with a pattern-controlled movable traveler, of a work support, a tool, electro-magnetic means for controlling the tool, and contact devices controlled by the movement of the traveler, the same comprising a movable actuator having a movement greater than that of the traveler and contacts with associated circuits adapted to be controlled thereby. 90
7. In a machine of the class described, the combination with a tool, of means for causing pattern-controlled actuation thereof, a rotary pattern support, a turn-table having a plurality of rotary work supports, a driving gear arranged coaxially with relation to said turn-table, inter-meshing gears one for each rotary work support, and means for driving said first named gear at a rate proportioned to the speed of rotation of the pattern support. 95
8. In a machine of the class described, the combination with a pattern support, of a work support, a traveler, a tool carrier, a feed carriage for the traveler, a feed carriage for the tool carrier, driving means for each carriage, a feed screw and nut for each driving means for imparting simultaneous feed for both said carriages, the same including a worm and gear drive, a worm shaft mount- 100
- 120
- 115
- 125

ed at one end to swing about an axis, releasable holding means to hold said shaft and maintain said worm and gear in mesh, means to disengage the worm from said worm gear when said holding means is released, and tripping means to release said holding means when the traveler feed carriage has completed its traverse.

9. In a pattern-controlled reproducing machine, the combination with a pattern support, of a work support, a traveler and an actuating tool, a screw fed carriage to feed the traveler with relation to the pattern, a screw fed carriage to feed the tool with relation to the work support, common driving mechanism for actuating said feed carriages, means for automatically disengaging said driving mechanism at a predetermined point on the traverse of said carriages, and means manually to return said carriages to their initial position.

10. In a pattern-controlled reproducing machine, the combination with a rotary pattern support, of a rotary work support, driving means therefor, a traveler operatively related to the pattern support, a reciprocatory tool operatively related to the work support, carriages for said traveler and tool carrier respectively, mechanism for feeding said carriages simultaneously to cause relative traverse between the traveler and the pattern support and the work support and the tool, and devices for driving said feed mechanism from said driving means at any one of a plurality of speeds to simultaneously vary the traverse of said carriages with relation to the speed of rotation of the pattern and work supports.

11. In a pattern-controlled reproducing machine, the combination with a pattern support and a pattern traveler, of a tool and its work support, pattern-controlled electro-magnetic means for actuating the tool with relation to the work, the latter including a magnet for moving the tool toward the work, an armature, and means to adjust the relative position of the magnet to the armature to maintain a minimum air gap.

12. In a pattern-controlled reproducing machine, the combination with a pattern support and a pattern traveler, of a tool and its work support, pattern-controlled electro-magnetic means for actuating the tool with relation to the work, the latter including a magnet for moving the tool away from the work, an armature, and means to adjust the relative position of the magnet to the armature to maintain a minimum air gap.

13. In a pattern-controlled reproducing machine, the combination with a work support and a reciprocatory tool, of a magnet for moving the tool toward the work, a magnet for withdrawing the tool from the work, and means for preventing the parts acted upon by the magnets from having contact

with the magnet cores in the extreme position of the tool.

14. In a pattern-controlled reproducing machine, the combination with a work support, of a tool carrier, a guide support 70 for the carrier, a guide foot adapted to engage the work, said guide support being movable toward and away from the work support under the control of the guide foot, actuating devices for the tool carrier 75 to effect a reciprocation thereof, and means to vary the extent of movement of the tool toward the work with relation to the guide foot and to vary the depth of its working stroke with relation to the work. 80

15. In a pattern-controlled reproducing machine, the combination with a work support, of a tool carrier, a guide support for the carrier, a guide foot adapted to engage the work, said guide support being 85 movable toward and away from the work support under the control of the guide foot, actuating devices for the tool carrier to effect a reciprocation thereof, and means automatically to vary the extent of movement of the tool toward the work with 90 relation to the guide foot and to vary the depth of its working stroke with relation to the work.

16. In a pattern-controlled reproducing machine, the combination with a work support, of a tool carrier, a guide support for the carrier, a guide foot adapted to engage the work, said guide support being movable toward and away from the work 100 support under the control of the guide foot, actuating devices for the tool carrier to effect a reciprocation thereof, means to vary the extent of movement of the tool toward the work with relation to the guide foot 105 and to vary the depth of its working stroke with relation to the work, and a supplemental pattern mechanism for controlling said variation.

17. In a pattern-controlled reproducing machine, the combination with a reciprocatory tool carrier, of a guide support therefor, a guide foot adapted to engage the work, said guide support being movable to and from the work under the control of the 110 guide foot, and devices for reciprocating the tool. 115

18. In a pattern-controlled reproducing machine, the combination with a work support, of a pattern-controlled reciprocatory tool, a guide support therefor movable toward and away from the work, and electro-magnetic actuating devices for the tool also carried by said guide support. 120

19. In a pattern-controlled reproducing machine, the combination with a work support, of a pattern-controlled reciprocatory tool, a guide support, a guide foot, said guide support being movable toward and away from the work through control of 130

the guide foot, and devices to adjust the extent of reciprocatory movement of the tool.

20. In a pattern-controlled reproducing machine, the combination with a pattern, of a traveler having pattern-controlled movement, contacts controlled by the movement of said traveler, and a condenser to shunt around said contacts.

21. In a pattern-controlled reproducing machine, the combination with a pattern, of a traveler with means for causing relative traverse between the traveler and the pattern, a reciprocatory working tool, a work support, electro-magnetic devices and circuit connections controlled by the traveler for moving said tool toward the work, and auxiliary devices for making and breaking said circuit connections to modify the tool movement.

22. In a pattern-controlled reproducing machine, the combination with a pattern, of a traveler with means for causing relative traverse between the traveler and the pattern, a reciprocatory working tool, a work support, electro-magnetic devices and circuit connections controlled by the traveler for moving said tool toward the work, and auxiliary devices for making and breaking said circuit connections to modify the tool movement, the same comprising a toothed wheel with means for rotating the same and a circuit controlled contact actuated by said wheel.

23. In a pattern-controlled reproducing machine, the combination with a pattern support, of a traveler device for causing relative movement between the traveler and the pattern, the latter having a varying contour to cause movement responsive to the varying contour of the pattern, a tool and a work support, electro-magnetic means and circuit connections for moving the tool, a contact controlled by the reciprocatory movement of the traveler for controlling said circuit connections, and electro-magnetic means and supplemental means for making and breaking said circuit connections to modify the action of the tool.

24. In a pattern-controlled reproducing machine, the combination with a pattern support adapted to support a pattern of varying contour, of a traveler with means for causing relative traverse between the same and the pattern, said traveler having movement toward and away from the pattern responsive to the varying contour of the latter, a reciprocatory working tool and its work support, electro-magnetic devices and circuit connections controlled by the movement of the traveler for moving the tool toward the work when said traveler encounters the depressions in said pattern and for moving the same away from the work

when it encounters the elevations thereof, and auxiliary circuit controlling means adapted rapidly to interrupt the inward impulses of the tool toward the work to cause the same to vibrate when the traveler engages the depressions in the pattern.

25. In a pattern-controlled reproducing machine, the combination with a pattern support, of a traveler, a work support, a reciprocatory tool, electro-magnetic means for actuating said tool through said traveler from the pattern, and a rosetting attachment comprising a rotary circuit breaking device and means for varying the speed of rotation thereof.

26. In a pattern-controlled reproducing machine, the combination with a main pattern, of an auxiliary pattern, a work support and a tool, electro-magnetic means dependent on the main pattern to actuate the tool according to a predetermined pattern design, and electro-magnetic means controlled by the auxiliary pattern to modify the action of the tool and thereby to superpose on said main design a supplemental design following said auxiliary pattern.

27. In a pattern-controlled reproducing machine, the combination with a work support, of a reciprocatory tool, electro-magnetic means for actuating said tool with relation to the work, a pattern, a traveler for controlling said electro-magnetic means, and electro-magnetic means for automatically varying the extent of movement of the tool toward the work.

28. In a pattern-controlled reproducing machine, the combination with a work support, of a tool, pattern-controlled means for reciprocating the tool, and pattern-controlled electro-magnetic means for varying the extent of movement of the tool.

29. In a pattern-controlled reproducing machine, the combination of a main rotary pattern support, of a traveler, an auxiliary pattern support, a traveler operatively related thereto, means for simultaneously feeding said travelers across their respective supports in contact with the patterns thereon, a rotary work support, a reciprocatory tool operatively related thereto, electro-magnetic means for reciprocatively moving said tool under the control of said main traveler, electro-magnetic means for varying the extent of movement of said tool under the control of said auxiliary traveler, and means for feeding said tool across the work support.

30. In a pattern-controlled reproducing machine, the combination with a pattern-controlled reciprocatory tool carrier, of a guide support, a threaded member engaging said tool carrier and determining the extent of working movement thereof toward the work, and electro-magnetic devices operatively related to said threaded member and

adapted during the operation of the tool to move the same to vary the depth of the working stroke.

31. In a pattern-controlled reproducing machine, the combination with a pattern-controlled reciprocatory tool carrier, of a guide support, a threaded member engaging said tool carrier and determining the extent of working movement thereof toward the work, electro-magnetic devices operatively

related to said threaded member and adapted during the operation of the tool to move the same to vary the depth of the working stroke, and pattern-controlled means for energizing and deenergizing said electro-magnetic means. 15

In testimony whereof, we have signed our names to this specification.

CLINTON F. SMITH.
JEAN B. SABOURIN.
